Inventor:

Luther C. Voorhees,
by Drane & Co., Attys.

UNITED STATES PATENT OFFICE.

LUTHER C. VOORHEES, OF NEW YORK, N. Y.

BOX-LOOP FOR BRIDLES.

SPECIFICATION forming part of Letters Patent No. 309,173, dated December 9, 1884.

Application filed April 24, 1884. (No model.)

To all whom it may concern:

Be it known that I, LUTHER C. VOORHEES, a citizen of the United States, residing at New York, in the county of New York and State of New York, have invented certain new and useful Improvements in Box-Loops for Bridles, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is more especially to reduce the cost of constructing bridles for horses; and it consists in the arrangements and combinations of parts, substantially as will be hereinafter set forth, and embodied in 20 the clauses of the claims.

Referring to the accompanying drawings, in which similar letters of reference indicate like parts in each of the figures, Figure 1 is a plan showing the several parts of the cheek piece 25 and winker sewed together prior to forming the box-loop. Fig. 2 is a section through line *x*, and Fig. 3 is a section through line *y*. Figs. 4 and 5 are sectional views showing the arrangements of parts when the device is 30 complete.

In said drawings, *a* is the winker, formed with the usual stiffening-plate and projecting laterally from the cheek-strap to cover the animal's eyes. *b* is the said cheek, and *c* is a loop-piece laid over said winker in a position such as to allow, when the parts are sewed together, free edges *g* to be bent over to form the loop, as shown in Fig. 1. Billets or leveling-pieces *e* are placed at the sides of the winker, 40 as shown in Fig. 2, to provide a uniform surface for the box-loop. Lines of stitching *f f* are then sewed through the parts *a b c e*, securing said parts together, but leaving free edges *g g*, adapted to be bent to overlap one 45 another as in Figs. 4 and 5, and to be secured together to form a loop. Said edges are reciprocally skived, as shown in Figs. 3, 4, and

5, so that when taken together they form a thickness of leather equal to the rest of the loop. The overlapping edges are then cemented together with a waterproof cement and placed in a die and there firmly united. After this the loop is dampened and placed in suitable dies, and thus pressed into shape for the market. The overlapping edges may, to 55 secure greater permanence, be tacked together, as in Fig. 5, the points of the tacks being clinched in such a manner as to be concealed. I may also, should I desire so to do, arrange a strengthening plate or strip, *h*, between the rows *f f* of stitching, as in Fig. 4, to give greater stiffness to the loop.

I am aware that it is not new to form a box-loop of a piece, the edges of which are cemented together, and I do not claim the same herein.

Having thus described the invention, what I claim as new is—

1. In a bridle, the box-loop, the winker, and the cheek-strap sewed together by lines of stitching *f f*, and a plate *h*, arranged between said lines of stitching, substantially as set forth.

2. In a bridle, the combination of the cheek-strap, the winker laid thereon, and loop-piece *c*, having the edges *g g* cemented together, and the rows of stitching *f f* passing from the inner corners of the loop through the winker and cheek-piece and securing said parts together, all substantially as and for the purposes set forth.

3. In a bridle, the combination of the cheek-strap *b*, the winker *a*, the leveling-pieces *e*, and the loop-piece *c*, said parts being united by the rows of stitches *f f*, and said loop-piece having free edges *g g*, adapted to be secured together to form a loop, all substantially as set forth.

In testimony that I claim the foregoing I have hereunto set my hand this 22d day of April, 1884.

LUTHER C. VOORHEES.
